UNITED STATES PATENT OFFICE

LOUIS HOFFMAN, OF ST. PAUL, MINNESOTA, ASSIGNOR TO STEAM PRESSING IRON COMPANY, OF CHICAGO, ILLINOIS, A CORPORATION OF DELAWARE

PRESSING IMPLEMENT

Original application filed November 20, 1922, Serial No. 602,085. Divided and this application filed May 7, 1928. Serial No. 275,850.

My invention relates to a pressing implement such, for example, as a flat iron or tailor's goose, of the type provided with means for ejecting moisture in the form of steam against the goods or garment being pressed, and this application is a division of my copending application, Ser. No. 602,085, filed November 20th, 1922, which application has eventuated into Patent No. 1,687,562, granted Oct. 16, 1928.

One of the objects of the invention is to construct the implement that when the moisture supplied thereto is in the form of water it will be quickly generated into steam and vaporized and ejected against the work in a dry, highly heated, state. A difficulty experienced heretofore with water fed steam pressing irons has been that when the iron was used continuously for a considerable period of time the generating surfaces became cooled and as a result a wet steam, or even water, was ejected from the perforations in the pressing face of the implement. My present invention insures a complete vaporization of the water by employing certain novel constructions and arrangements to be hereinafter described and claimed.

Another difficulty encountered in connection with the use of water supplied steam pressing irons arises from the tendency of the fluid ducts and ports to become sealed and clogged with mineral deposits from the water. The scaling of the ducts in which the water is vaporized is likely to prevent the rapid flashing of the water into steam. The deposit of mineral solids may go so far as to clog the fluid passages entirely. An important object of my present invention is to provide an implement with a steam generating plate upon which the water is delivered and which receives any mineral deposit that may occur when vaporization takes place. It is the intention that the water be completely transformed into steam before it leaves this element of the implement so that no scaling can take place in the ducts and ports between the plate and the pressing face of the implement. The plate is preferably formed and arranged so that any deposit of mineral solids may be readily re-

moved. For example, the plate is preferably channeled on its upper surface to provide an open water duct and is assembled with the other parts of the implement in such manner that it may be easily removed for 55 cleaning. To insure the complete vaporization of the water a heating device is arranged adjacent to, preferably directly under, the plate and the fluid outlet from the channel of the plate is in an upward direction. 60

A further object is to provide means whereby the steam generated as aforesaid is superheated before being directed to the perforated pressing face of the implement. This expedient prevents condensation and 65 maintains or increases the pressure and temperature of the steam, thereby making the operation of the device more reliable and efficient.

A further object of the invention is to 70 provide a steam pressing iron which will be simple in its construction and can be inexpensively manufactured.

The invention consists in the new and improved constructions, arrangements and devices to be hereinafter described and claimed for carrying out the above stated objects and such other incidental objects as will be referred to in the following description of the preferred embodiment of the invention shown 80 in the accompanying drawings.

In the drawings,

Figure 1 is a vertical sectional elevation of my improved form of pressing implement; and

Figures 2, 3 and 4 are sectional views, in plan, taken on the lines, 2—2, 3—3, and 4—4, respectively of Fig. 1.

Referring to the drawings:

The body of the iron consists of a hollow 90 member 1, and two plates 2, 3, secured together and to said hollow member by screws 4 or other suitable fastening means. The recess 5 of the hollow member 1 is closed at the back by a door 6 formed with a gas burner 95 7 supplied with gas from flexible pipe 8. The steam generating duct 9 which is of sinuous configuration (Fig. 2) is formed between the plates 2 and 3. Ready access is given to the duct for removal of scale by unscrewing 100

the screws 4. Water enters duct 9 through of the flexible water pipe 10, the nipple 11 of which is screwed into a boss 12 in the top of the plate 3, which is formed with a perforation 13 communicating with duct 9. The steam generated in duct 9 passes downwardly through passageway 14 formed in a boss 15 at one rear corner of the member 1 into a superheating duct 16 (Fig. 3) composed of a series of communicating passageways formed in member 1 back and on opposite sides of a depression or recess 17 in the lower part of said member, the purpose of which is to bring the heat from burner 7 as close as possible to the distributing duct in the base portion 18 of the implement. The passageways constituting duct 16 may be formed, for convenience in manufacture, so that they extend through the sides of the member 1 and the ends of the ducts closed by plugs 19. After the steam has passed through duct 16 along the path as indicated by the arrows in Figure 3, it goes through a rising passageway 20 in a boss 20^a on the inside of member 1 and through aligning ports 21, 22 and 23 in plates 2, 3, and valve casing 24 secured to plate 3, to a chamber 25 in the valve casing and from there through a down passageway 26, 27, 28, 29, to a distributing duct 30 in the base 18 of the iron which consists preferably of a pair of diagonally disposed passageways 31 converging toward the toe of the iron connected by transverse passages 32 and 33. The pressing face perforations 34 lead from the distributing duct. Communication between duct 23 and duct 26 is controlled by a valve 35 having a stem 36 in threaded relation at 37 with a bonnet 38 screwed into the side of valve casing 24. The valve 35 is opened and closed by means of a thumb piece 39 on an angular arm 40 fastened to the end of stem 36, the stem extending through a stuffing box 41 on bonnet 38. Any suitable means may be employed for providing a vent from chamber 25 to the atmosphere for relieving pressure in the steam generating and superheating ducts when valve 35 is closed. I have shown an automatically operated relief valve 42 for such purpose.

It will be observed that the steam generating superheating and distributing ducts are arranged so that they are effectively heated by the flame in recess 5. The ducts are of relatively small cross sectional area in comparison to their length which makes it possible to effectively convert the water into steam and develop a steam pressure in the iron insuring ejection of steam through the pressing face perforations at considerable velocity and elevated temperature, thereby accomplishing the penetration of the work by the steam jets which is essential particularly with heavy fabric. The aggregate length of the ducts is considerable, the walls of the body

of the implement quite thin, and the arrangement of the ducts such that all three of the ducts are, throughout their length, exposed to the heat produced within the hollow body of the implement. The products of combustion escape from the space 5 through a port 43 at the forward end of the iron.

Realizing that the principles of my invention could be utilized in other embodiments from that herein shown, I wish to be understood as claiming all modifications within the scope of the appended claims.

Having thus described my invention, what I claim and desire to secure by Letters Patent, is:

1. In a pressing implement of the moistening type adapted to be supplied with water for generation into steam and ejection as such against the work, the combination of a hollow body having a perforated pressing face, a heating device in said hollow body, and a pair of plates separably secured together at the top of said hollow body and formed so as to provide between them a steam generating space to receive the water supplied to the implement connecting said steam generating space to the perforated pressing face.

2. In a pressing implement of the moistening type adapted to be supplied with water for generation into steam and ejection as such against the work, the combination of a hollow body having a perforated pressing face, a heating device in said hollow body, and a pair of plates separably secured together at the top of said hollow body and formed so as to provide between them a circuitous steam generating duct of small cross sectional area in comparison with its length to receive the water supplied to the implement, connecting said steam generating space to the perforated pressing face.

3. In a pressing implement of the moistening type adapted to be supplied with water for generation into steam and ejection as such against the work, the combination of a hollow body having a perforated pressing face, a heating device in said hollow body, and a pair of plates separably secured together at the top of said hollow body and formed so as to provide between them a steam generating space to receive the water supplied to the implement, said hollow body having formed in its base a duct for distribution of the steam to the pressing face perforations and at the sides of the recess therein with a superheating duct, connecting said steam generating space to the perforated pressing face.

4. In a pressing implement of the moistening type adapted to be supplied with water for generation into steam and ejection as such against the work, the combination of a body having a perforated pressing face, a heating device in said body, plates removably secured to said body and formed with a steam

generating duct therein to receive the water supplied to the device, said body being formed in its base with a duct for distribution of the steam to the pressing face perforations and at the sides with a recess therein having 5 a superheating duct communicating with the distributing duct and generating duct, said ducts being of small cross sectional area in comparison with their length.

10 5. In a pressing implement of the moistening type, the combination of a hollow body, the base of which has a perforated pressing face, a heating device in said body, and means removably secured to said body and being 15 formed with a steam generating duct adapted to receive a moistening fluid, said body having formed in its sides a superheating duct communicating with the generating duct, and the base with a duct communicating with the 20 superheating duct for distributing steam to the perforations of the pressing face.

In testimony whereof I affix my signature.
LOUIS HOFFMAN.
